UNITED STATES PATENT OFFICE.

FRANK C. KENNETT, OF BROOKLYN, NEW YORK.

FOLDING BOX.

Application filed August 28, 1923. Serial No. 659,746.

To all whom it may concern:

Be it known that I, FRANK C. KENNETT, a citizen of the United States, residing at 664 East 23rd Street, borough of Brooklyn, 5 in the county of Kings and State of New York, have invented a new and useful Folding Box, of which the following is a specification.

My invention relates to improvements in 10 folding boxes constructed of cardboard, pasteboard or other suitable material; and the objects of my improvement are to provide a folding box which shall be capable of being set in display position or in a flat 15 position, and which will not be subject to collapse of the easel when in display position.

I attain these objects by the mechanism illustrated in the accompanying drawings in 20 which, Fig. 1 is a plan view of body A which consists of one unit of pasteboard or other suitable material; Fig. 2 is a plan view of back and easel B which consists of one unit of pasteboard or other suitable material; Fig. 3 is a plan view of band C; Fig. 4 is a perspective view from the front and side of the entire device when assembled and in display position; Fig. 5 is a direct view from the back of the entire device when assembled and in display position. Fig. 6 is a perspective view from the back and side of the entire device when assembled and in flat position; and Fig. 7 is a direct view from the bottom of the entire device when assembled and in flat position.

Similar letters and numerals refer to similar parts throughout the several views.

A is the body, with side flaps A¹ with 40 creases A² between, and with front flap A³ with crease A⁴ between, and back flap A⁵ with crease A⁶ between, and cover A⁷ with crease A⁸ between. B is the back, with easel B¹ with crease B² between, and with side flaps B³ with creases B⁴ between, and with upper flap B⁵ with crease B⁶ between, B⁷ are outer easel flaps, which are separated 45 from side flaps B³ by creases B². Inner easel flaps B¹¹ are separated from outer easel flaps B⁷ by creases B⁴, and from easel B¹ by creases B¹⁰. B⁹ are sides bearing flaps which 50 are separated from outer easel flaps B⁷ by creases B⁸. Side bearing flaps B⁹ are separated from back bearing flap B¹³ by cut lines B¹⁶. Easel B¹ connects with back bear-

ing flap B¹³ by crease B¹⁴. C is the band with ends C¹ with creases C² between.

In assembling the complete structure, back B is glued or otherwise affixed to back flap A⁵, and band ends C¹ are glued or otherwise affixed to side flaps B³. 60

The operation of my device is as follows: Let us assume that the body A shown in Fig. 1 and its integral side flaps A¹, front flap A³, back flap A⁵ and cover A⁷ are all 65 flat in the same horizontal plane. Now bend side flaps A¹ into vertical position on creases A², bend front flap A³ into vertical position on crease A⁴, bend back flap A⁵ into vertical position on crease A⁶, which will place cover 70 A⁷ also in vertical position.

Next place back B of Fig. 2 on the back of back flap A⁵ and in alignment therewith; and then bend forward the side flaps B³ and outer easel flaps B⁷ on creases B⁴, and with 75 adhesive or other attaching means, fasten side flaps B³ to the outer rear face of side flaps A¹.

Next place band C on the outer face of front flap A³ and in alignment therewith, 80 and then bend backward the ends C¹ on creases C², and with adhesive or other attaching means, fasten ends C¹ to the outer face of side flaps B³.

When the device has been assembled 85 as stated, it will be in the position shown in Figs. 4 and 5 wherein the outer easels B⁷ are in parallelism with side flaps A¹, side flaps B³, and ends C¹, which holds the device in display position. And as 90 shown in Figs. 4 and 5, in order to make this display position more stable than in the devices known to the prior art, side bearing flaps B⁹ are folded outward along creases B⁸, and back bearing flap B¹³ is 95 folded backward along crease B¹⁴.

Now, if it be desired to place the device in flat position, the function is as follows:

First bend side bearing flaps B⁹ back into alignment with outer easel flaps B⁷, and 100 bend back bearing flap B¹³ and intermediate flap B¹⁵ into alignment with easel B¹.

Then press outer easel flap B⁷ inward and upward along crease B², and press inner easel flap B¹¹ inward and upward along 105 creases B⁴ and B¹⁰, whereupon outer easel flaps B⁷ will be parallel with and immediately under body A, and inner easel flap B¹¹ will be parallel with and immediately in front of easel B¹. 110

Then bend easel B¹ forward along crease B² until easel B¹ with inner easel flaps B¹¹ are immediately under and parallel with body A, and the entire device is then in flat position as shown in Figs. 6 and 7.

I claim:

In a folding box, an easel composed of inner flaps, outer flaps, a back bearing flap, and side bearing flaps, the creases between

the inner flaps and the outer flaps being substantially at right angles with the crease between the back bearing flap and the main body of the easel, and the crease between each inner flap and the main body of the easel making an angle less than ninety degrees to the adjoining crease between said inner flap and its adjoining outer flap.

FRANK C. KENNEDY.
